UNITED STATES PATENT OFFICE.

EDWARD S. WINCHESTER, OF DORCHESTER, MASSACHUSETTS.

LATCH.

SPECIFICATION forming part of Letters Patent No. 416,308, dated December 3, 1889.

Application filed February 14, 1889. Serial No. 299,899. (No model.)

To all whom it may concern:

Be it known that I, EDWARD S. WINCHESTER, of Dorchester, in the county of Suffolk and State of Massachusetts, have invented 5 certain Improvements in Door-Latches, of which the following is a specification.

This invention relates to an improvement in that class of latches represented in an application filed by me on the 14th day of February, 1889, Serial No. 299,900, in which a pivoted latch-bolt is maintained in a retracted position against the influence of a projecting spring by a detent or catch, which is arranged to be lifted out of contact with the latch-bolt 15 by a releasing device acting thereon in a lateral direction when the door encounters the door-jamb.

In the present invention a spring detent or catch is arranged to frictionally engage a 20 swinging latch-bolt on its end, so that the same can be held thereby at any point in its path of movement, the said detent being combined with a releasing device acting laterally thereon to release the bolt.

25 In the accompanying drawings, Figure 1 is a horizontal cross-section through my improved lock and a portion of the door-jamb. Fig. 2 is a section of the same on the line *xx*. Fig. 3 is a section on the line *yy*.

30 Referring to the drawings, A represents the lock-casing, consisting, as usual, of the outer casing *a* and the inner casing *a'*.

B and B' represent the inner and outer knobs, respectively, the former provided with 35 the shank *b* and the latter with the spindle *b'*, which passes therethrough and is screwed or otherwise suitably fastened to the knob B.

C is a spring located on the spindle between the shank and the knob to prevent end motion of these parts.

40 D are tumblers formed on the shank, as usual, by which reciprocating frames E E' are operated in a manner similar to my application above referred to.

45 F represents a latch-bolt pivoted in the end of the casing by the pivot-pin *f* and formed with the side walls *f' f²* and an end wall *f³*.

G represents a spring for projecting the 50 latch-bolt, which encircles the pivot-pin and bears on the latch-bolt and casing of the latch, respectively.

H represents a bail pivoted between the walls of the latch-bolt and extending therefrom in position to be engaged by the reciprocating frames E E'.

55

The foregoing parts are in all respects identical with the corresponding parts in my application above referred to, and it will suffice to merely refer to them incidentally herein.

I represents a spring detent or catch having 60 one end securely fastened to the inner face of the outer casing *a* and extending therefrom in the path of the outer curved end of the swinging latch-bolt. This detent is arranged to bear on the outer end of the swinging latch- 65 bolt and to frictionally hold the same until lifted out of contact therewith by a releasing device, hereinafter described. It will be observed that by means of this detent, arranged 70 in the manner shown, the bolt may be either held in a wholly-retracted position or in a partially-retracted position, as desired. As the bolt is usually wholly retracted, I have provided the detent with a projection or a shoulder *f*, adapted to engage within a notch 75 *t*, formed in the outer surface of the latch-bolt, the position of the notch with relation to the shoulder being such that the latter will enter the notch when the bolt is wholly retracted. This construction enables the spring 80 to more securely hold the latch and serves as a stop to limit the inward motion.

In order that the detent may be lifted out of contact with the latch-bolt to release the same, I provide the sliding plate *K*, which is 85 mounted in the end of the casing. This plate is provided with the central tongue *k*, which extends between the walls of the latch in contact with the free end of the detent, as shown. It is further provided on either side of the 90 central tongue with the two tongues *k'* and *k²*, which extend forward, and serve to guide the plate.

L represents a plate or projection secured to the jamb of the door in position to encounter the end of the plate *K* when the door is closed, and acts to push the plate inward and lift the detent out of engagement with the latch-bolt, and thus release the same.

95 It is to be understood that I do not confine myself to the exact construction shown for frictionally holding the latch-bolt, as the same 100

can be variously modified without departing from the limits of my invention, the essence of which consists in a detent arranged to bear on the outer end of a swinging latch-bolt and 5 to frictionally hold the same in any position to which it may be retracted.

Having thus described my invention, what I claim is—

1. In a latch, the latch-bolt pivoted at one 10 end and having its opposite end free to move in the arc of a circle, a spring for projecting said latch-bolt, suitable mechanism for retracting the same, and a detent arranged to bear on the end of the latch-bolt and to frictionally hold the same in any position to which 15 it may be retracted, in combination with the lateral releasing device adapted to lift the detent out of engagement with the latch-bolt.

2. In a latch, the latch-bolt having one end pivoted and the opposite end provided with 20 the notch *t* and free to swing in the arc of a circle, the bolt-projecting spring, the detent arranged to bear upon and hold the end of the latch-bolt frictionally, and having also the shoulder to engage the bolt and positively 25 hold the same when fully retracted.

In testimony whereof I hereunto set my hand, this 21st day of January, 1889, in the presence of two attesting witnesses.

EDWARD S. WINCHESTER.
